CLAIM

The ornamental design for a processing machine, as shown and described.

DESCRIPTION

FIG. 1 is a right side elevational view of a processing machine showing my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view; and,

FIG. 7 is a perspective view of the processing machine. The broken lines in the drawings depict portions of the processing machine that form no part of the claimed design.
